UNITED STATES PATENT OFFICE

EMILE AUGUSTIN BARBET, OF PARIS, FRANCE

APPARATUS FOR THE FRACTIONATION OF HEAVY OILS

Application filed May 8, 1928, Serial No. 276,150, and in France May 12, 1927.

It is easy to separate the volatile constituents contained in hydrocarbons and particularly in crude petroleum by steam, owing to their low boiling points, but it is difficult to fractionate lubricating oils the boiling points of which are so high that steam distillation is not possible.

There is however the possibility of super-heating the steam, but it then turns into a true gas, having a specific temperature which is low, the co-efficient of heat exchange being unfavourable and necessitating large heating surfaces.

One is therefore obliged to heat the apparatus by direct firing, but heating under these conditions always provokes cracking, which produces deposits of coke upon the inner side of the boiler. The necessity of stopping the fractionation for cleaning the boilers puts the apparatus out of action for a relatively long period of time.

The process and apparatus which will be described has for its object to avoid these difficulties. A vacuum is employed in order to bring down the boiling points of the oil by 70 to 90° C. according to the kind of products treated.

On the other hand, considering that it is mostly the heating with direct firing which provokes cracking, it is necessary to avoid reaching boiling temperature in the direct fired boilers.

Let us suppose that, in a first, continuous apparatus which can be of any design, the crude petroleum has already been deprived of its light and heavy fractions, up to the temperature of say 160° to 170° C., which temperature can be easily obtained by means of steam generators working at a pressure of 10 kgs. per sq. centimeter.

The accompanying drawing does not include this first apparatus, but the first column B is already under vacuum and is required for separating white spirit and lamp oils.

Crude petroleum free from volatile frac-

tions, and having a temperature of about 160° C. enters the automatic feeding vessel A having a float feed. The column B, being under vacuum, the oil is drawn in and enters at part b. There is a sudden expansion 50 which instantaneously vaporizes the greater part of the lighter products. It has been proved that this sudden expansion could give in vapours, products having, under normal pressure, a boiling point up to 250° C. However, the amplitude of this self-evaporation is limited by the heat of the crude petroleum freed from volatile fractions which is under treatment.

The vapours thus formed from the petroleum ascend through the plates of the rectifying column B. The remaining liquid flows in the usual way onto the lower plates B' and passes then into the tubular heater C, which receives the full pressure of the steam generators by which the heating is effected.

The petroleum vapours produced by the heater C ascend, owing to the vacuum, through the plates B' provoking the ebullition of the lighter hydrocarbons which join the other 70 evaporated hydrocarbons and ascend together, through the plates B reaching the condenser D which is effective enough to condense and to cool the distillate.

The outlet for the distillate is provided 75 with the separation vessel d. At the top of said vessel a pipe connects it with the receiver V and another pipe P connects this receiver with the vacuum pump, which is not shown on the drawing. One portion of the liquid distillate flows into the sight glass 1 and it is white spirit; another portion is returned through pipe line 2 to the top of the column B; two successive extractions are made from 80 the plates, in 3 and in 4. The products of these two extractions are cooled in the cooler E and are sent thence to the sight glasses 5 and 6, connected with vacuum in order to 85 permit outlet.

The extract from 3 is high grade petroleum; the extract from 4 is common petroleum i. e. containing a small quantity of heavier oil.

5 Every sight glass is connected with a small vacuum vessel and the plant is equipped with the necessary number of small pumps for drawing the liquids into these three vacuum vessels and driving the fractionated 10 products out into the storage tanks.

The central column F is similar to the column BB'; and also operates under vacuum, but its purpose is to separate the products boiling at high temperatures, one cannot 15 therefore apply steam coil heating as in the case for column BB'.

The crude petroleum deprived of its lamp oils, coming from C is therefore heated in the direct fired boiler HH' to a temperature 20 below boiling but sufficient to heat it up to about 220° C.

A pump P' extracts the residue from the vacuum heater C and drives it through line cc' to the top of the boiler HH'. After warming up, the liquid passes through the valve h and ascends by pipe pp' up to the bottom of column F, where it is also instantaneously vapourized by the vacuum obtaining in column F the lighter products being vapourized i. e. all those boiling, under normal pressure, at about 300° C. The lightest fractions will leave the column through condenser G and separator g ultimately reaching the test glass 7. The surplus of the liquid will descend through line 8 and enter the top of column F. From this column two further extractions are made at points 9 and 10, exactly in the same way as previously described for column B.

40 These extracts from 9 and 10 reach respectively the test glasses 12 and 13, connected with vacuum chambers.

This column will therefore give, as in column B, three fractions constituting three 45 fractions of oil, having different properties depending upon the oil initially treated.

The liquid coming from the bottom of the column F (which contrary to the column B has neither lower exhaustion plates nor heater) pass to another direct fired boiler, which will warm it up to about 260/270° C. i. e. at least 50° C. under its boiling point at normal pressure.

50 Pump P² drives the residue from the column F through the pipe line ff into the boiler KK'. The product heated up leaves this boiler through valve k and ascends through line m up to the receiver L.

All that can be volatilized under influence 60 of vacuum and of this temperature, is instantaneously vaporized, and ascends through line 1 up to the coil M.

The exit vessel of the coil is under vacuum, 65 its upper part being connected by a tube with a vacuum vessel V.

The condensed liquid, which is an extremely dense and viscous oil, comes out through test glass 14, connected like the others to a vacuum vessel.

The unvolatilized part leaves the vessel L 70 by line N, a pump not shown on the drawing being employed to effect the removal of this portion. This residue is mazout.

One has thus, with the aid of the described apparatus reached the final point which it 75 is possible to obtain from crude petroleum by distillation.

Between the boilers HH' and KK' the drawing represents another similar boiler QQ' which may serve as spare boiler either 80 for HH' or KK'. The methodical warming up without boiling does not result in cracking, it could nevertheless, after a long period of time, produce some carbon deposit which ought to be eliminated. This deposit is of course very small, not only because the oils are merely warmed up, but also because of the fact that the limit of this warming is still 85 by 50 or 60° C. lower than the boiling points 90 these oils possess under normal pressure.

It is known that cracking takes place more readily, the higher the boiling point of the oil under treatment; this is the reason why almost every cracking process implies heating under pressure, in order to elevate this 95 boiling point.

One spare boiler will be sufficient since cleaning has to be done very seldom.

One can easily provide piping and taps 100 allowing, when desired, the spare boiler QQ' to be filled either with the liquid contained in HH' or in KK'. This decanting can be made either by pumping or by the aid of slightly compressed air.

The warming up boilers being under normal pressure, are represented in shape of two superposed cylinders in order to utilize the heat of the fires to the best advantage, but they can of course comprise a single cylinder 110 or many cylinders in order to aid the heating throughout the mass of oil during the continuous warming up of the liquid, from its entering to its exit.

What I claim is:

Apparatus for the continuous rectification 115 of hydrocarbons for the fractionation of heavy oils from petroleum which has been deprived of its more volatile constituents, comprising, a rectification column adapted to operate under vacuum whereby the lighter products are removed, a steam heater for said column, a heating boiler, means for passing the residue from said column into the heating boiler where it is heated by direct heat 120 to a temperature below its boiling point, a second rectifying column, means for supplying the heated residue of the first rectifying column to the said second rectifying column, 125 which latter is adapted to operate under vac- 130

uum whereby lubricating oils are fractionated, a second heating boiler, means for passing the residue of the said second column into said second heating boiler where it is heated 5 by direct heat to a temperature below its boiling point and means for supplying the heated residue from said second heating boiler to a vacuum vessel, whereby further fractionation takes place leaving a residue of 10 mazout.

In testimony whereof I have signed my name to this specification.

EMILE AUGUSTIN BARBET.
